UNITED STATES PATENT OFFICE.

WOLDEMAR HOMMEL, OF ZURICH, SWITZERLAND.

RABBLE FOR MECHANICAL ROASTING-FURNACES.

1,220,513.

Specification of Letters Patent. Patented Mar. 27, 1917.

Application filed August 23, 1916. Serial No. 116,568.

To all whom it may concern:

Be it known that I, WOLDEMAR HOMMEL, of Zurich, Switzerland, a citizen of the Swiss Republic, temporarily residing at 5 Clausthal a. Harz, Germany, have invented certain new and useful Improvements in Rabbles for Mechanical Roasting-Furnaces, of which the following is a specification.

My invention relates to rabbles for mechanical roasting furnaces in which the rabble- or scraper-blades are moved to and fro at right angles to the direction of travel of the ore or other material to be roasted.

Roasting furnaces of this kind heretofore 10 employed gave rise to the inconvenience of the ore or other material to be roasted accumulating unnecessarily along both longitudinal walls of the furnace where it remained and was therefore temporarily lost 15 for the roasting effect.

The object of my present invention is to eliminate this undesirable feature by making the blades of the rabble of a particular shape, described hereinafter. As is known 20 the working faces of scraper blades which cause the ore to travel along the hearth of the furnace are set perpendicular to the hearth-level or bottom and obliquely to the traveling direction of the rabble. Two series of such blades are necessary. They are 25 working alternately in such a manner that by every movement of the rabbles in the one or the other direction the working faces of the other series conveying it in the opposite 30 direction across the hearth, the ore is brought forward one step along the hearth.

Now, it is not to be avoided that with each stroke the blades of the non operative or idle series will push aside a certain small 35 amount of ore and that this ore will accumulate along the longitudinal walls of the hearth.

A further object of my invention is to 40 avoid such undesirable accumulations of ore by giving the non operative or outward part of the blades a plow-like shape viz. an inclined face extending from the top of the working face downward to a horizontal, preferably sharp edge which engages and 45 travels over the hearth level. This arrangement causes the scraper blades of the idle series to penetrate into the under layers of the ore accumulated at the side of the hearth in such a way, that a part of this ore slides 50 over the upwardly extending faces of the blades and drops toward the middle of the

hearth. But even with blades of such a shape small accumulations of ore cannot completely be avoided, as still small quantities of ore collect in the spaces between two adjacent blades.

Another object of my invention is to avoid such accumulations by bridging the spaces between the blades by means of suitable stays which also have inclined faces and remove thereby the top of the small ore heaps or accumulations formed between the blades.

In the accompanying drawings:

Figure 1 is a side view of the rabble according to my invention. Fig. 2 is a plan view of this rabble. Fig. 3 is a cross-section on the line A—B, Fig. 2; Fig. 4 is a perspective view of a scraping blade; Fig. 5 is a section through the blades on the line C—D, Fig. 2; Fig. 6 is a view showing the position 75 of the blades when conveying the ore toward the left; and Fig. 7 is a sectional view of the furnace showing the way of working of the rabble according to my invention.

Referring to the drawings, *a* is a hollow beam which is reciprocated as shown in Fig. 7 in a known manner transversely with regard to the longitudinal axis of the furnace by means of a rod *b* guided in the furnace wall, Fig. 7. Fixed to the beam *a* are two groups or series I and II, each containing a number of blades *c* each of which blades has a working face *d* perpendicular to the hearth level, as shown in Fig. 3. The blades of each series are arranged in an image-like or mirrored and a staggered way with regard to the blades of the other series, so that when the rabble moves to and fro, the whole of the ore to be roasted is stirred up and is alternately moved forward longitudinally of 85 the furnace by the working faces *d* in a known way so that when the rabble moves in the direction of the arrow 1 Figs. 2 and 7, the ore is conveyed by the blade series I, the blade series II producing the same effect 90 when the rabble moves in the direction of the arrow 2.

In order to cause the ore conveyed by one of the blade series to be completely caught by the other blade series these series of blades 105 are not transposed to the extent of a full blade-width or interval, but they are so placed that the edges of the blades of each series reach into the working radius of the blades of the other series.

The faces *e* adjoining the inclined perpendicular working faces *d* of each blade

are sloping downwardly and outwardly, preferably as shown in Fig. 3, so that they form cutter-like sharp edges *g* with the ground-faces or bases *f* of the blades. By 5 these down sloping outer faces the blades obtain a wedge-like shape.

The way of working of the so shaped blades is clearly shown in Fig. 7. When 10 the rabble moves in the direction of the arrow 1 from the left to the right transversely over the hearth level, merely the working faces *d* of the blades of series I shown in dotted lines in Fig. 7, perform the conveyance of the ore longitudinally of the furnace, whereas the blades of series II take no 15 part in this conveyance. The blades of series II would rather move the ore placed in front thereof along if they were provided with a face perpendicular to the hearth- 20 level and parallel to the longitudinal axis of the furnace and they would cause this ore to be conveyed toward the right longitudinal wall of the furnace, where it would accumulate. But as the blades of series II are 25 provided with sharp edges sliding over the hearth level, adjacent to which is the face *e*, extending upwardly, the ore will now slide over these faces *e* toward the middle of the hearth and drop over the top edge of the 30 blades, as shown by the arrows on the right of Fig. 7, so that any objectionable accumulations of ore along the longitudinal walls of the hearth which would disturb the working 35 of the furnace, are eliminated.

When the rabble moves in the direction 40 of the arrow 2, the blades of series II convey the ore longitudinally of the hearth, whereas now the edges *g* and the faces *e* of the blades of series I penetrate under this ore and cause it to fall toward the middle 45 of the hearth as already described.

In order to avoid accumulations of ore 50 between the blades alongside the longitudinal furnace walls the blades *c* are connected with each other on their outer parts by webs or stays *i* bridging the space between each two blades *c*. The upper side or face of each stay passes directly into the adjacent blade faces *e* and has an outward down-slope similarly to the faces *e*.

The bridge-like stays *i* being wedge-shaped, enter into the ore, on the left similarly to the blades of the rabble, as shown in Fig. 7. In doing so, they act as ductors or 55 strippers as they only take off the accumulations above the required layer of ore and push it back toward the middle of the hearth. Therefore the bridges or stones *l* which have heretofore been arranged in the 60 doors *h* of the furnace *h* and having the height of the lateral ore accumulations and which make the surveyance of the furnace very difficult, can now be made considerably lower, for instance as shown in dotted 65 lines in Fig. 7.

In addition each of the blades *c* has a vertical web *m* arranged in the direction of the rabble-motion at the side of the down-sloping face *e*, this web ending outwardly by a cutterlike edge *n* as shown in Fig. 4. 70 Preferably this cutting edge directly joins the outer cutting edge *g* of the blades. By means of these webs *m* ending by cutter-edges, the blades can more easily penetrate into the ore. They also help by pushing the 75 accumulated ore up the wedge-like surfaces *e* of the blades.

Adjoining the cutter-like outer edge *g* of each blade and also at the side of the down-sloping wedge-life face *e* each blade is 80 further provided with a small perpendicular face *o*. This inclined face acts as an auxiliary face and is intended to push away particularly along the longitudinal walls of the 85 furnace cavity the ore situated under the bridge-like stays and to feed it toward the working faces *e* proper.

The blades and consequently also their working faces must be arranged as shown in Fig. 2 or Fig. 6, according to whether the 90 ore is to be conveyed to the right or to the left. This arrangement of the blades is necessary when the roasting furnace has two hearths lying one above the other and when the rabbles of both hearths are moved together. 95

The blades *c* may form parts of the beam *a* or be rigidly fixed to it. But preferably the blades are arranged in such a manner that they can be removed from the beam 100 each one separately or in groups, in order to be readily inspected or replaced and in order to allow of varying the dimensions of the hollow space. There can be any desired number of blades and they can be fixed on 105 the rabble in any desired way. The bridge-like connecting stays *i* can also be dispensed with as well as the auxiliary working faces *o*.

The outwardly down-sloping faces of the 110 blades need not necessarily reach down to the basis of these blades; under certain conditions it will also do if they reach down approximately to one half of the height or thickness of the ore-layer on the hearth 115 level.

What I claim as new and desire to secure by Letters Patent is:

1. In a rabble for a mechanical roasting furnace having two groups or series of 120 scraper blades arranged alternately or staggered relatively to each other and provided with inclined working faces arranged perpendicularly to the hearth level, on each of the blades an outwardly down-sloping face *e* 125 adjoining the inclined working face acting like a plow-blade.

2. In a rabble for a mechanical roasting furnace having groups or series of scraper blades arranged alternately or staggered 130

- relatively to each other, provided with inclined working faces arranged perpendicularly to the hearth level and outwardly 5 downsloping faces on each of the blades adjoining the inclined working face acting like a plow-blade, an outwardly downsloping face *e* forming a cutter-like sharp edge *g* with the basis of the respective blade.
3. In a rabble for a mechanical roasting 10 furnace having groups or series of scraper blades arranged alternately or staggered relatively to each other, provided with inclined working faces arranged perpendicularly to the hearth level and outwardly 15 downsloping faces on each of the blades adjoining the inclined working face acting like a plow-blade, bridge-like stays *i* connecting the blades with each other.
4. In a rabble for a mechanical roasting 20 furnace having groups or series of scraper blades arranged alternately or staggered relatively to each other, provided with inclined working faces arranged perpendicularly to the hearth level and outwardly
- downsloping faces on each of the blades ad- 25 joining the inclined working face acting like a plow-blade, a vertical web *m* adjoining the cutter-like outer face of each blade and also ending like a cutter.
5. In a rabble for a mechanical roasting 30 furnace having groups or series of scraper blades arranged alternately or staggered relatively to each other, provided with inclined working faces arranged perpendicularly to the hearth level and outwardly 35 downsloping faces on each of the blades adjoining the inclined working face acting like a plow-blade, a small inclined perpendicular face *o* adjoining the cutter-like outer edge *g* of the blade laterally of the down- 40 sloping face.

In testimony whereof I have signed my name to this specification, in the presence of two subscribing witnesses.

WOLDEMAR HOMMEL.
